COMBINATION COMB AND LIQUID RESERVOIR

Herbert Heinrich, Ridgewood, N.J., assignor to Coty, Inc., New York, N.Y., a corporation of Delaware

Application October 4, 1957, Serial No. 47,983

Term of patent 14 years

(Cl. D86—8)

I claim:

The ornamental design for a combination comb and liquid reservoir, substantially as shown.
